UNITED STATES PATENT OFFICE.

CASPER C. DU BOIS, OF NOBLESVILLE, INDIANA.

MIRROR OR PICTURE HANGER.

SPECIFICATION forming part of Letters Patent No. 438,066, dated October 7, 1890.

Application filed March 26, 1890. Serial No. 345,438. (No model.)

To all whom it may concern:

Be it known that I, CASPER C. DU BOIS, a citizen of the United States, and a resident of Noblesville, in the county of Hamilton and State of Indiana, have invented certain new and useful Improvements in Mirror or Picture Hangers; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a partly sectional and partly side view of my invention. Fig. 2 is an enlarged broken detail view thereof, and Fig. 3 is a rear perspective view of the mirror and its adjunctive parts.

This invention relates to certain improvements in mirror or picture hangers; and it consists in the novel construction and combination of parts, as hereinafter disclosed.

In the drawings, the letter A designates a plain board of suitable dimensions, adapted to be suspended or hung upon the wall or other suitable place in practice.

D is a mirror suitably suspended in position by means of interconnecting hooks and eyes d d', the former connecting with the board A and the latter connecting with the

mirror-frame. The mirror is adjustable at the desired angle by means of a rod e, pivoted thereto and having a loop d² engaging an elongated staple-like frame d³, secured to the board A'. This rod e has also an additional loop d⁴, engaged by a pin or key d⁵, also engaging any one of a vertical series of apertures e' in the board A.

It is obvious that the entire contrivance may be removed and transferred from place to place in any convenient manner and again be put up at one operation for use wherever desired.

Having thus described my invention, what I claim, and desire to secure by Letters Patent, is—

The combination, with the board having the staple-like frame and a vertical series of apertures, of the mirror having the pivoted rod provided with loops, one at its lower end and the other near thereto, and the pin or key engaging the end loop and said series of apertures, substantially as and for the purpose set forth.

In testimony whereof I affix my signature in presence of two witnesses.

CASPER C. DU BOIS.
